UNITED STATES PATENT OFFICE.

JAMES F. LESTER, OF NEW YORK, N. Y., ASSIGNOR TO RICHARD MERRIFIELD, OF NEW YORK, N. Y.

WASHING-MACHINE.

1,172,296.

Specification of Letters Patent. Patented Feb. 22, 1916.

Application filed August 7, 1915. Serial No. 44,195.

To all whom it may concern:

Be it known that I, JAMES F. LESTER, a citizen of the United States, and a resident of the borough of Manhattan, city, county, 5 and State of New York, have invented certain new and useful Improvements in Washing-Machines, of which the following, taken in connection with the accompanying drawings, is a specification.

10 My invention relates to washing machines of the cylinder type and has for its principal object to provide a mechanism by which a more intense agitation of and cleansing action upon the fabrics being washed is attained than by the use of the ordinary machine of this type.

Other objects will be particularly pointed out or will otherwise appear in connection with the following description of the embodiment of my invention which is shown in the accompanying drawings in which—

Figure 1 is a vertical axial section of a cylinder type washing machine containing my invention, and Fig. 2 is a cross section 25 thereof on the line 2—2 of Fig. 1.

The apparatus illustrated consists of a suitably supported cylindrical casing or container 3 provided with alined, central bearings at its ends in which the journals 4 of 30 the perforated cylinder or drum 5 are adapted to rotate. This drum has end walls to which the journals 4 are rigidly attached, and peripheral rods connected to and extending between said walls, the diameter of 35 said walls and the perforated body portion of the drum formed by said rods being somewhat less than the internal diameter of the casing 3 so that a space is formed between the drum and casing whereby the drum may 40 freely rotate within said casing. The casing and the drum are provided with suitable doors 6 and 7 respectively so that access may be had to the interior of the drum when the doors are in open position, for inserting 45 the clothes to be washed and removing the same after they have been washed.

One of the journals 4 is connected with the driving mechanism which is constructed in any known and approved fashion whereby 50 the drum may be driven a definite number of rotations in one direction and then reversed so as to rotate a definite number of revolutions in the opposite direction. This driving mechanism, as shown, may be driven 55 by the motor 8, and may consist of the worm

gearing 13 connected by suitable gearing so as to drive the horizontal shaft 24; upon this shaft are loosely mounted bevel gears meshing with diametrically opposite sides of the gear 25 fixed upon the journal 4, and 60 suitable clutch mechanism is provided whereby the bevel gears are alternately caused to be driven by the shaft 24, thus rotating the gear 25 and with it the cylinder 5 first in one direction and then in the other 65 direction.

Mounted upon the casing 3 is a condenser 9 and above the condenser is mounted a suitable vacuum producing device, such as the centrifugal pump 10, the inlet pipe 11 for 70 which pump passes through the condenser and communicates with the space above the drum and between it and the casing and the discharge orifice 12 of which pump communicates with the atmosphere. The pump 75 10 may be driven in any suitable manner, as for example by the motor 8. The condenser 9 is provided with an inlet pipe 14 and an outlet pipe 15 for causing a cooling fluid, such as water, to circulate through the condenser and cool the vacuum pump inlet pipe 11.

Within the casing near the bottom thereof and between said casing and the rotary drum is a longitudinally extending pipe 16 85 provided with distributing branches 17, these branches being in turn provided with a plurality of apertures. The longitudinal pipe 16 is connected with a pipe 18 which extends through the bottom of the casing 90 and then, externally of the casing, to a point beyond the end thereof where it rises to a level above the normal level of the cleaning solution in the casing. Slightly above this level the pipe 18 is connected 95 with a branch pipe 19 which is provided with a valve 20 and communicates beyond this valve with the atmosphere. The pipe 18 may extend in any suitable way beyond the branch pipe 19 and is provided beyond 100 the branch pipe with a valve 21; this extension of the pipe 18 may, if desired, communicate with a heated water supply system so that said pipe may be employed for introducing water into the casing. A suitable valved drain conduit 22 is also provided for the casing.

Extending longitudinally and secured to the interior of the casing below the normal water level thereof are baffles 23, one being 110

located on one side of the center of the casing and the other, preferably at an equal distance from and on the other side of said center. These baffles 23 preferably extend 5 the full length of the casing and are each composed of a rigid portion firmly secured to the casing and a flexible portion, which may be a rubber strip, one edge of which is firmly secured to the rigid portion and 10 the other edge of which extends toward and is substantially in contact with the periphery of the body portion of the drum 5. The baffles thus extend substantially completely across the space between the drum and the 15 casing.

In the operation of the device, the drum may be rotated so that the door 7 thereof registers with the casing door 6. Both doors may be opened and the fabrics to be 20 washed, together with soap or other cleansing agent, may be introduced into the drum. The fabrics, if desired, may be contained in a net. The doors may now be closed and fastened in closed position. If desired hot 25 water may be introduced through the casing door opening before it has been closed. Or the hot water may be introduced through the pipes 18, 16 and 17, the valve 21 being open and the valve 20 being closed. When 30 sufficient washing solution has been provided the valve 21 is closed and the valve 20 is opened to the desired degree. The driving motor is now started and the drum is caused to rotate back and forth in the 35 usual manner. The starting of the motor 12 which may also serve as the driving motor, causes the vacuum pump 10 to operate so as to tend to produce a vacuum in the machine above the solution therein. This 40 vacuum will ultimately cause air to be drawn through the pipes 18 and 16 and to emerge from the apertures in the distribution pipes 17, the casing, of course, being fluid tight. Upon emerging from the apertures 45 the air will rise in bubbles through the water and clothes interstices and will ultimately enter the vacuum pipe 11 and the pump 10 and be discharged therefrom through the orifice 12 into the atmosphere. 50 The washing solution being at boiling temperature, or nearly so, will give off condensable vapors or gases such as steam, and this steam is condensed in the vacuum pipe, because the latter is maintained cool by the 55 condenser, and the condensed steam drips back into the casing. The maintenance of the vacuum therefore does not result in an appreciable removal of water from the apparatus. 60 The baffles are of importance in preventing the air bubbles from rising through the space between the drum and casing and in causing substantially all of the air to enter the perforations or slits between the drum rods and pass through the drum and 65

its contents on their way to the surface. The valuable function of these baffles will readily be appreciated if the fact is borne in mind that the fabrics in the drum are carried alternately somewhat up the sides 70 of the drum during the reverse rotations thereof and that air entering from below on the side holding the bulk of the clothes will encounter the resistance of these fabrics and will therefore tend to escape through 75 the annular path between the drum and casing. Moreover, the rotation of the drum and its contents will set up swirls or currents in the water which will tend to draw the air bubbles through such a path. The 80 provision of the baffles effectually prevents such escape of air and insures that all of it will penetrate the drum and the fabrics therein.

The passage of the air bubbles produces a 85 violent agitation of the clothes and this agitation is communicated continuously to new portions thereof because the drum rotation continuously turns over the clothes and brings different portions thereof into contact with the ascending air currents. The effect of this additional violent agitation is that the clothes are washed more quickly and thoroughly than has been possible heretofore by drum rotation only; furthermore 90 the forcing of the air through the fabric interstices will drive out the solution held therein, and the dirt with it, and will in addition create strong currents in the solution which will pass through the fabric and 95 in themselves produce a cleansing action which would not be had if air were not bubbled through the liquid. Any method for producing these air bubbles may be employed but I prefer the vacuum method described for the reason principally that it insures a greater ebullition effect. 100

I claim:

1. A washing machine comprising a casing adapted to contain a washing solution, a perforated cylinder rotatably mounted in said casing, means for rotating said cylinder, means for producing a vacuum in the upper part of said casing above the level of the washing solution, means for admitting fresh air at atmospheric pressure into said casing below the said cylinder, and baffle means below the solution level for causing substantially all of said air to pass into the cylinder through the perforations thereof. 110 115 120

2. A washing machine comprising a casing adapted to contain a washing solution, a perforated cylinder rotatably mounted in said casing, there being a space between the periphery of the cylinder and the inner surface of the casing, means for rotating said cylinder, means for producing a vacuum in the upper part of said casing above the level of the washing solution, means for admitting fresh air at atmospheric pressure into 125 130

5 said casing below the said cylinder, and baffle means extending substantially completely across the above mentioned space below the solution level for causing substantially all of said air to pass into the cylinder through the perforations thereof.

10 3. A washing machine comprising a casing adapted to contain a washing solution, a perforated cylinder rotatably mounted in said casing, there being a space between the periphery of the cylinder and the inner surface of the casing, means for rotating said cylinder, means for producing a vacuum in the upper part of said casing above the level 15 of the washing solution, means for admitting fresh air at atmospheric pressure into said casing below the said cylinder, and baffle means extending substantially completely across the above mentioned space below the solution level for causing substantially all of said air to pass into the cylinder through the perforations thereof, said baffle means comprising a rigid longitudinally extending portion secured to the casing and a flexible portion, one edge of said flexible portion being secured to said rigid portion and the other edge thereof being in substantial contact with the periphery of said drum.

20 4. A washing machine comprising a casing adapted to contain a washing solution, a perforated cylinder rotatably mounted in said casing, there being a space between the periphery of the cylinder and the inner surface of the casing, means for rotating said cylinder, means for causing fresh air at atmospheric pressure to pass upwardly

25 through the cylinder, and baffle means extending substantially completely across the above mentioned space below the solution level whereby the passage of the air through said space is prevented.

5. A washing machine comprising a casing adapted to contain a washing solution, a perforated cylinder rotatably mounted in said casing, means for rotating said cylinder, means for producing a vacuum in the upper part of said casing above the level of the washing solution, a condenser for cooling a part of said vacuum producing means whereby the escape of condensable vapors is prevented, and means for admitting fresh air at atmospheric pressure into said casing below the said cylinder.

6. A washing machine comprising a casing adapted to contain a washing solution, a perforated cylinder rotatably mounted in said casing, means for reversibly rotating said cylinder, means for producing a vacuum in the upper part of said casing above the level of the washing solution, a condenser for cooling a part of said vacuum producing means whereby the escape of condensable vapors is prevented, and means for admitting fresh air at atmospheric pressure into said casing below the said cylinder and baffle means below the solution level for causing substantially all of said air to pass into the cylinder through the perforations thereof.

70 In testimony whereof I have hereunto set my hand.

JAMES F. LESTER.
